EMMETT G. DETRICK, OF VICKSBURG, MISSISSIPPI.

PNEUMATIC HAMMER.

1,108,834.

Specification of Letters Patent. Patented Aug. 25, 1914.

Application filed September 25, 1913. Serial No. 791,803.

To all whom it may concern:

Be it known that I, EMMETT G. DETRICK, a citizen of the United States, residing at Vicksburg, in the county of Warren and State of Mississippi, have invented a new and useful Pneumatic Hammer, of which the following is a specification.

This invention has reference to improvements in pneumatic hammers, and is to be understood as useful for any purpose where a rapid succession of blows is desired.

It is the object of the present invention to provide a pneumatic hammer structure of extreme simplicity and at the same time one that is reliable in operation and not liable to become disabled because of the presence of obstructing matter, since the device of the present invention is largely self cleaning and is free from all complicated parts.

In accordance with the present invention there is provided a freely reciprocable plunger or hammer designed to deliver a succession of blows to a suitable tool or tool holder and the body of the structure has certain ducts and ports to which the hammer is related as a reciprocable valve, while the exhaust is always freely open and hence offers no impediment at any time to the escape of air. The structure is furnished with valves which, however, are springless and respond solely to air pressure, and these valves are so related to the hammer that the air for their operation is not afterward directed to the hammer, wherefore the full and direct force of the air is always utilizable for the reciprocation of the hammer.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is a longitudinal section of a pneumatic hammer embodying the invention, and showing the plunger at the termination of its active stroke. Fig. 2 is a section on the line 2—2 of Fig. 1. Fig. 3 is a fragmentary section similar to Fig. 2 and showing the hammer at

the beginning of its active stroke. Fig. 4 is a section on the line 4—4 of Fig. 1. Fig. 5 is a perspective view of a valve block employed in the structure. Fig. 6 is an end view of the valve block as seen from the opposite end to that shown in Fig. 5. Fig. 7 is a section on the line 7—7 of Fig. 4.

Referring to the drawings, there is shown an elongated body member 1 usually cylindrical in cross section and terminating at one end in a laterally expanded head 2. Extending axially through the body 1 is a bore 3 which may be of equal diameter throughout, and is laterally expanded into a counterbore 4 within the head 2. That end of the bore 3 remote from the head 2 contains a sleeve 5 having a longitudinal passage therethrough of smaller diameter than the bore 3, and this sleeve is designed to receive a stem 6 on the corresponding end of a tool holder 7 such as is customarily employed in pneumatic hammers, the term hammer being used as comprehensive enough to cover the use of the tool of the present invention for any purpose to which it is applicable.

Extending longitudinally through the body member 1 to one side of the bore 3 is a duct or passage 8 of a length equal to that of the bore 3 between the counterbore 4 and the inner end of the sleeve 5, but at one point this duct 8 is interrupted by a web or wall 9. The duct 8 has ports 10, 11, 12 and 13 opening therefrom into the bore 3 at respectively different points. The ports 11 and 12 are on opposite sides of the web or wall 9, while the port 10 is between the port 11 and the head 2, and the port 13 opens into the bore 3 closely adjacent to the inner end of the sleeve 5. On the opposite side of the body 1 or at any other appropriate point the body 1 has another longitudinal passage 14 of less length than the passage 8, and this passage has ports 15 and 16 opening into the bore 3. The port 15 is closer to the head 2 than the port 10 and the port 16 is located between the ports 12 and 13 in the direction of the length of the body 1, but closer to the port 12 than to the port 13.

At other points about the body member 1 are longitudinal ducts or passages 17 and 18, respectively, exterior to the bore 3, the passage 17 being as long as the passage 8 and provided at the end corresponding to the inner end of the sleeve 5 with a port 19 opening into the bore 3, the ports 13 and 19 being located at about the same distance from the

head 2. The passage 18 is shorter than the other passages and extends from the head 2 but a relatively short distance and at its inner end is provided with a port 20 opening into the bore 3 closer to the head 2 than the port 10. For convenience the passages 8, 14, 17 and 18 are disposed about the bore 3 in approximately ninety degree relation, but this is not obligatory. However, for reasons which will hereinafter appear, the passages 17 and 18 are arranged approximately diametrically opposite one to the other. The passage 18 is also provided at the end adjacent to the counterbore 4 with a port 21 opening into the bore 3.

Fitted to the bore 3 so as to reciprocate therein freely yet snugly, is an elongated hammer or plunger 22 having a reduced central portion 23 producing a groove 24 circumferentially about the middle part of the plunger.

Seated in the counterbore 4 is a block 25 shown as cylindrical in form, although not necessarily so, but such form is the most convenient to construct. Diametrically through the block 25 is a passage 26 having laterally expanded ends 27 each closed by a screw plug 28 and from each expanded portion 27 there extends a port 29, 30, respectively, in alignment with the respective passages 17 and 18, and constantly open thereto. Each enlargement 27 where it joins the corresponding end of the passage 26 is formed into a valve seat 31 adapted to receive a valve 32, 33, respectively, each having a stem 34 entering the passage 26, and these stems are of such length that when one valve is seated the other valve is held away from its seat. The passage 26 at about a midpoint communicates constantly with a passage 35 extending radially through the block 25 and opening at the periphery thereof and near the outer end this passage 35 has a port 36 in line and constantly communicating with the passage 14.

Extending through the block 25 in parallelism with the axis thereof is another passage 37 in constant communication with the passage 8 where it opens into the counterbore 4, while still another passage 38 is formed through the block 25 parallel with the axis of the block to accommodate a pin 39 having one end seated in a socket 40 appropriately formed in the head 2, so that when the block 25 is lodged within the counterbore 4 the pin 39 maintains it in proper position. The pin 39 is to be taken as typical of any suitable means for holding the block 25 in constant relation with the parts with which its passages communicate.

The head 2 is seated in a socket member 41 having a handle 42 formed on or secured thereto and the handle 42 need not differ materially from handles as customarily provided for pneumatic hammers. In the

drawings the exterior of the head 2 and the portion of the socket member 41 receiving the head 2 are shown as correspondingly screw threaded, but even in this particular showing of the drawings need not be strictly followed. The head 2 has formed therethrough a radial passage 43 communicating with an opening or port 44 through the socket member 41 and the passages 43 and 44 are in line with the passage 35 and in constant communication therewith. Since the parts may not always fit accurately the inner wall of the head 2 is provided with a circumferential groove 45 and numerous passages 46 are formed through the head in addition to the passage 43, while the inner wall of the socket member 36 has a circumferential groove 47 formed therein so that there is always free communication between the passage 14 and the atmosphere, as well as between the passage 35 and the atmosphere.

The socket member 41 is formed with a passage 48 in line with the passage 37 and may have a threaded entrance 49 adapted to receive an air hose, while this passage 48 is normally traversed by a valve 50 under the control of a manipulating lever 51 on the handle 42, so arranged that when the handle is grasped the valve 50 may be opened thus admitting air to the passage 8. The valve 50 and its manipulating devices may follow the usual practice and hence need no special description. The socket member 41 is formed with a shallow recess 52 where coming in contact with the block 25 so that air entering the tool may be distributed certainly to the passage 37.

Let it be assumed that in the state of inaction the parts are in the position shown in Fig. 1 with the plunger 22 against the stem 6 at the end of the bore 3 remote from the head 2. Under these circumstances one of the valves 32 or 33 is seated, but it is immaterial which one this may be. The operator grasps the handle 42 and by pressure on the lever 51 causes the opening of the valve 50 and air under pressure is admitted to the passage 8, it being assumed that an air hose is connected to the socket 49. In the position of the parts assumed the port 10 is closed or blanked by the corresponding larger end of the plunger 22 and the port 20 is also closed thereby, while the other larger end of the plunger 22 closes the port 16. However, the ports 11 and 12 are in communication through the groove 22 then bridging these ports, and the port 13 is opened to the bore 3 between the corresponding end of the plunger and the inner end of the sleeve 5, the plunger being held away from the sleeve by a slight projection of the stem 6 into the bore 3. Air under pressure therefore finds its way along the passage 8 through the port 11 into the groove 24 and from thence by

way of the port 12 into the continuation of the passage 8 on the other side of the web 9 and by way of the port 13 into the bore 3 and exerts its pressure upon that end or head of the plunger 22 at the time engaging the stem 6. The air under pressure also finds its way from the bore 3 through the port 19 into the passage 17 and from thence into the enlargement 27 containing the valve 33 and if at the time this valve is open, the air under pressure immediately closes it and at the same time causes the opening of the valve 32. The compressed air at once impels the plunger 22 away from the stem 6 toward the block 25 and this causes the progressive closing of the ports 12 and 11 and the ultimate opening of the port 10 to the groove 24. The initial movement of the plunger 22 is unimpeded because air within the bore 3 between the plunger and the head 25 finds ready escape through the port 15 into the exit passage 14 which is always in free communication with the atmosphere through the port 36, passage 35 and passages 43 and 44. The plunger quickly closes the port 15, but still there is an exhaust passage for air within the bore 3 between the plunger and the block 25 by way of the ports 21 and 30, and the passage 26 where opened by the valve 32, said passage 26 being at all times in free communication with the atmosphere through the passage 35. The expansive force of the air is exerted upon the plunger to move it toward the block 25 until ultimately the port 20 is uncovered by the corresponding end of the plunger, and is thereby placed in communication with the grooves 24 intermediate of the plunger, and at this time the port 10 is also in communication with the groove 24, so that compressed air entering the passage 8 finds ready access to the passage 18, whereupon live air finds ready access to the valve 32 and as this live air is under greater pressure than the air tending to hold the valve 33 closed, the latter valve is forced open and the valve 32 is closed, thus cutting off the escape of air from the bore 3 between the plunger and the block 35 before the plunger reaches the block 25, and, moreover, the rapidly diminishing space within the bore 3 receives air under full pressure through the port 21. Simultaneously with the establishment of the conditions just named the other end of the plunger has moved to a position to uncover the part 16 to the end of the bore 3 first receiving air under pressure, while the passage 17 always communicating by the port 19 with the end of the bore 3 remote from the block 25 is now in communication with the atmosphere through the open valve 33. The rapid accumulation of air pressure between the plunger and the block 25 not only interposes a strong air cushion preventing the plunger from reaching the block 25, but full

air pressure at once acts upon the block 25 to drive it toward the stem 6 which it strikes with all the force imparted to it by the air pressure behind it, for air pressure is not again established at the striking end of the plunger until the port 12 is uncovered, which does not take place until approximately the time that the blow is struck. Then, and then only, is there established an air pressure sufficient to reverse the valves and return the plunger to the beginning of its power stroke.

The air cushion established between the plunger and the head 25 at the termination of the retractive movement of the plunger prevents any shock or jar which might occur should the plunger strike metallic parts, and also does away with the necessity of a buffer spring, while at the end of the power stroke the full force of the plunger is utilized without the retardation by the establishment of buffering pressure or the presence of a buffering spring.

Experience has shown that the plunger will reciprocate at high speed, say, about two thousand strokes per minute, while the power of the stroke is in excess of that of commercial forms of pneumatic hammers of like air consumption.

No springs whatever are used in the working parts of the hammer, the two valves employed being responsive solely to air pressure, and this air pressure is not weakened by performing work before it reaches the valves, nor does any of the compressed air do any work before reaching the plunger. Full power is therefore available for all the work performed and the parts respond vigorously and with full efficiency.

The passages and ports can be made of exceptionally large size, so that any particles liable to choke small passages, and which sometimes find access thereto, have no material effect upon the device of the present invention and should small particles of grit or the like find their way into the passages and ports the plunger readily forces them out on its return stroke. Even should the valves 32 and 33 leak to some extent, it only means a slight waste of air without a material reduction in the efficiency of the device.

All the ports through which the main air passes are controlled by the plunger and the only valves other than the plunger itself have to do with the control of exhaust air and not with main air acting upon the plunger.

What is claimed is:—

1. A pneumatic hammer comprising an elongated body member with a longitudinal bore, a live air duct leading into one end of the bore and having its continuity immediately interrupted and there having ports opening into the bore on each side of the interruption, two other ducts each having a

1. A plurality of ports leading into the bore, with one of said two ducts opening constantly to the atmosphere and the other of said two ducts constituting both a live air and an exhaust duct, means responsive to live air pressure for controlling the last-named duct to open and close it to the atmosphere, and a reciprocatory power plunger in the bore controlling certain of the ports opening into the bore.
2. A pneumatic hammer comprising an elongated body member with a longitudinal bore, a live air duct extending longitudinally through the body member and at one end opening into the corresponding end of the bore, said duct having its continuity intermediately interrupted and provided with ports opening into the bore on each side of the interruption, another duct shorter than the first-named duct and provided with a plurality of ports opening into the bore and said duct also opening constantly to the atmosphere, another duct in the body member having a plurality of ports opening into the bore; a fourth duct extending longitudinally of the body member and communicating with the bore at the end thereof into which the first-named duct leads, and a valve structure located at the opposite end of the body member and there communicating with the third and fourth named ducts, said valve structure being responsive to live air pressure supplied through the said ducts controllable thereby and opening and closing said ducts to the atmosphere.
3. A pneumatic hammer comprising an elongated body member with a longitudinal bore and a live air duct extending longitudinally through the body member and at one end opening into the corresponding end of the bore, said duct having its continuity intermediately interrupted and provided with ports opening into the bore on each side of the interruption, another duct shorter than the first-named duct and provided with a plurality of ports opening into the bore and said duct also opening constantly to the atmosphere, another duct in the body member having a plurality of ports opening into the bore; a fourth duct extending longitudinally of the body member and communicating with the bore at the end thereof into which the first-named duct leads, and a valve structure located at the opposite end of the body member and there communicating with the third and fourth named ducts, said valve structure being responsive to live air pressure supplied through the said ducts controlled thereby and opening and closing said ducts to the atmosphere, the valve structure comprising separate valves and including a duct constantly open to the atmosphere at an intermediate point and provided at opposite sides with oppositely directed valve seats for the valves.
4. A pneumatic hammer having an elongated body member provided with a longitudinal bore and with air ducts leading into the bore and spaced apart to direct air under pressure into opposite ends of the bore, and one of said air ducts also leading to the atmosphere, the body member being provided with an exhaust duct distinct from the other ducts and leading from the bore and open constantly to the atmosphere, a reciprocatory power plunger in the bore constituting a reciprocatory valve for the air and exhaust ducts, and means controlled by live air pressure for in turn controlling the exhaust of air from the bore through the live air duct communicating with the atmosphere.
5. A pneumatic hammer provided with an elongated body member having an elongated bore, and a reciprocatory plunger therein, said body member having air ducts with ports communicating with the bore and controlled by the reciprocatory plunger, certain of the ducts being arranged to receive live air under pressure and direct it against opposite ends of the plunger with one of the live air ducts leading to the atmosphere and another of the ducts serving solely as an exhaust duct, the device being provided with means responsive to air under pressure and arranged to be operated by live air other than that operating the plunger for controlling the exhaust of utilized air.
6. A pneumatic hammer comprising an elongated body member with an axial bore and a reciprocatory power plunger within the bore, a closure for one end of the bore having a transverse duct therein with valve seats at the ends and intermediately communicating with the atmosphere, valves mounted in the duct in operative relation to the valve seats, ducts leading through the body member and having ports communicating with the bore and the ports and plunger being related to cause the latter to operate as a controlling member for the ports, one of the ducts constituting a live air duct for supplying air under pressure, and another of the ducts constituting an exhaust duct at all times communicating with the atmosphere, and others of the ducts communicating with the valve in the closure to supply live air thereto for operating the valves.
7. A device of the type described comprising an elongated body member having an axial bore, and a reciprocatory plunger mounted therein, said body member being provided with a duct for live air and having ports communicating with the bore, another duct having ports communicating with the bore and also communicating with the atmosphere, a block forming a closure for one end of the bore, a reciprocatory valve structure within the block movable in a direction perpendicular to the longitudinal axis of

- the bore, and ducts in the body member communicating with the bore and with the valves, the reciprocatory plunger being related to the ports opening into the bore and 5 being constructed to control the ports to regulate the admission of live air to the bore to drive the plunger, and the admission of live air to the valves to control their action.
- 10 8. A device of the type described comprising an elongated body member with an axial bore and with a counterbored head at one end, said body member being also provided with longitudinally extended ducts having 15 ports communicating with the bore at different distances from the counterbore, a reciprocatory plunger lodged in the bore and constructed to operate as a reciprocatory valve for the ports, a block lodged in the 20 counterbore and having ports equal in number to the ducts in the body member and each communicating with a respective one of the ducts in the body member, and a valve structure in the block responsive to air supplied 25 through certain of the ducts, said valve structure controlling the exhaust of air from certain of the ducts and the plunger controlling the exhaust of air from the opposite ends of the bore.
- 30 9. A device of the type described comprising an elongated body member with an axial bore and having longitudinally disposed ducts in surrounding relation to the bore, one duct being provided with a break in its 35 continuity at an intermediate point with ports, two on opposite sides of the break and leading to the bore, and one of the ports entering the bore at one end thereof, another duct having spaced ports entering the bore, 40 and said duct being also provided with free communication with the atmosphere, another duct having a port communicating with the bore adjacent to the end port of the first-named duct, and still another duct communicating with the bore at its opposite ends 45 and of less length than the other duct, a block forming a closure for the correspond-
- ing end of the bore and provided with ports communicating with each of the said ducts in the body member, reciprocatory valves 50 within the block and each controlling a respective port other than those communicating with the first-named duct and the duct connected to the atmosphere, the block also having a passage communicating with the 55 atmosphere and controlled by the valves, and a plunger mounted in the bore to reciprocate therein and constructed to control the port opening into the bore.
10. A device of the type described provided with a reciprocatory power plunger and having live air ducts controlled by the power plunger for supplying air under pressure to operate the plunger, said device being provided with other live air ducts and 65 an air exhaust duct controlled by the plunger, and an exhaust valve structure communicating with the last-named live air ducts for receiving live air therefrom and in turn communicating with the atmosphere to exhaust the said last-named live air ducts. 70
11. A device of the type described provided with a reciprocatory power plunger and having live air ducts controlled by the power plunger for supplying air under pressure to operate the plunger, said device being provided with other live air ducts controlled by the plunger, and an exhaust valve structure communicating with the last-named ducts for receiving live air therefrom 80 and in turn communicating with the atmosphere to exhaust the last-named live air ducts, said device being also provided with an exhaust duct distant from the ducts controlled by the valve structure and wholly 85 controlled by the plunger.

In testimony, that I claim the foregoing as my own, I have hereto affixed my signature in the presence of two witnesses.
